FOOT SUPPORTER

Robert A. Davis, Jr., Nampa, Idaho

Application August 5, 1936, Serial No. 94,440

10 Claims. (Cl. 36—8.5)

This invention has reference to foot-supporters or stays such as are attached to or built into a boot or shoe to support the foot or ankle of the wearer.

5 A conventional form of arch supporter comprises a specially shaped stiff pad of leather or metal fixed within the boot or shoe to support and maintain the arch of the foot by pushing upwardly thereagainst. In another conventional form, the foot is suspended in a flexible pad or strap extending under the arch of the foot and adjustable for applying suspension pressure to the arch, the strap being adapted to encompass the in-step and suspended from the 10 upper of the shoe on the side thereof corresponding to the outer side of the foot.

The efficacy of the conventional forms of arch-supporters as a proper corrective for foot ailments is greatly offset by the considerable 20 foot-fatigue and discomfort suffered by the wearer due to the tendency of the supporters to restrict the free and natural movements of the foot.

The primary object of the present invention 25 is to provide a foot-supporter which adequately properly supports the foot without the disadvantage above mentioned and, with this end in view the present invention differs radically from accepted practice in that it provides for 30 flexible spring suspension of the arch of the foot from a more or less vertical position by means of a specially designed foot-supporter which gives a twisting lift, side and back pull to the arch and ankle while at the same time allowing 35 the foot to function and exercise in a substantially unrestrained and natural manner.

A further object of the invention is to provide a foot-supporter of the above-described character which is inexpensive in construction 40 and design and which can be either built into the shoe or boot or applied thereto as an attachment in a simple and convenient manner.

The objects and advantages of the invention are attained by the novel construction and arrangement of parts hereinafter fully described 45 and pointed out with reference to the accompanying drawing, wherein—

Figure 1 is a perspective view of a conventional shoe with the invention applied thereto;

50 Figure 2 is a cross section of the shoe as viewed in the direction from the toe to the heel;

Figure 3 is a view, in side elevation, of a part 55 of the shoe and illustrating the torsional bend or twist of the spring suspension unit of the invention.

The foot-supporter of the present invention, briefly described, comprises a spring suspension member and a flexible arch-engaging member connected together at one end and adapted to be fixed to a shoe at their other ends so as to extend vertically upward of the side of the shoe corresponding to the outer side of the foot; the arch-engaging member being held taut by the tension of the suspension member and the latter being adapted to be flexed or bowed to dispose its upper or suspension end vertically above the opposite or inner side of the foot when the arch-engaging member is pulled down into the shoe and into position under the arch of the foot by the pressure of the latter thereagainst.

In the embodiment illustrated, the spring suspension member consists of a length of flexible spring wire or rod having a normally straight shank portion 1 and a bent or bowed portion 1a; the latter terminating in a hook 2 for insertion 10 through an eyelet 3 in the arch-engaging member. The arch-engaging member is preferably a flexible strap or pad 4 of soft pliable leather or like material of a width to provide adequate 15 support surface for the arch of the foot.

In applying the device to a conventional shoe, such as illustrated at 5, a downwardly and transversely directed hole is drilled in the heel 6 near the forward edge of the latter externally of the shoe and lined with a metal ferrule or cup 7 to provide a socket for the reception of the end 8 of the spring rod 1. The socket 7 is preferably placed so as to be on the outer side of the shoe whether it be a right-foot shoe or a left-foot shoe. That is, the socket is located so as to 20 be on the side of the shoe corresponding to the outer side of the foot. The spring rod extends 25 vertically upward from the socket with its bowed end elevated above the top of the shoe and normally lying in a vertical plane substantially 30 at right angles to the horizontal plane of the shoe.

The strap 4, which is suspended from the hook 45 of the bowed portion, has its lower portion 4a disposed within the shoe and pivoted at its end to the shank of the inner sole at a point closely adjacent the location of socket 7 by means of a rivet or other fastener 9. The initial tension of the spring rod is such that, when the shoe is not upon the foot, the strap is held taut between 50 its lower shoe-attached end and its upper spring-suspended end and to one side of the shoe as indicated in dotted lines in Figure 2.

In use, the shoe may be placed upon the foot 55 with the supporter in either a coupled or un-

coupled state. In the first instance, the foot is inserted between the rod and the strap and pushed down into the shoe with the strap extending under the arch of the foot. In the second instance the uncoupled strap is laid crosswise within the shoe to extend beneath the arch of the foot with its eyelet end protruding upwardly and outwardly of the shoe on the inner side of the foot. The bowed end of the spring rod is then bent forward, and inwardly or sidewise, and downwardly to engage the hook with the eyelet. The position assumed by the foot-supporter when engaged with the foot is indicated in the full lines structures of Figures 2 and 3. With the foot fully inserted in the shoe and the strap under the arch of the foot, the outwardly extending portion 4b of the strap is disposed forwardly of the normal transverse vertical plane of the spring rod 1 with the result that the rod undergoes a torsional strain or twist when the portion 4b is pulled forward and over and downwardly to the opposite side of the shoe. In this flexed condition of the spring suspension the point of suspension of the arch represented at 2 and 3, is in a more or less vertical position above the arch of the foot on the inner side of the latter and since both the spring and the strap are spaced above the in-step, as indicated at x, there is no encompassing of the foot so as to restrict its free and natural movements. The pressure of the arch downward is opposed by the resistance of the flexed spring rod 1 and the latter, by reason of its natural tendency to regain its original position, exerts a torsional lift, side and back pull to the arch and ankle of the foot. The spring and strap thus provide flexible spring suspension of the arch from a more or less vertical position and at the same time allow the foot to function and exercise in a natural manner.

It is to be understood that the foregoing disclosure represents but one of several possible applications of the invention and that changes in form, structure and method of attachment may be resorted to within the scope of the appended claims.

Having thus described my invention what I claim is—

1. In a foot-supporter, the combination with a shoe of an arch-engaging element having one end attached to the shoe, and a spring suspension member attached to the shoe and supporting the free end of the arch-engaging element, said member being torsionally deformed to exert a twisting lift, side and back pull to the arch and ankle.
2. In a foot-supporter, the combination with a shoe of an arch-engaging element having one end attached to the shoe, and a bowed spring attached to the shoe and resiliently supporting the free end of the arch-engaging element, said bowed spring being torsionally deformed to exert a twisting lift, side and back pull to the arch and ankle.
3. A foot-supporter comprising a shoe, a transversely disposed arch-engaging element within the shoe to be passed under the arch of the foot, said arch-engaging element having one end attached to the shoe and having an eyelet in its free end, and a vertically disposed spring suspension member attached at its lower end to the heel of the shoe and having a hook at its upper end for insertion through the said eyelet of the arch-engaging element when said element is under the arch of the foot.
4. A foot-supporter comprising a shoe, an upstanding spring member fixed to the heel of the

shoe to extend vertically of the upper at the outer side of the shoe and an arch-engaging strap suspended at one end from the upper end of the spring member and at its lower end depending into the shoe and attached to the shoe at the outer edge of the shank of the insole, said strap being of a length that when held down in arch supporting position within the shoe by the pressure of the foot thereagainst the resultant flexing of the spring member is such as to dispose the upper end of the member inwardly over the shoe to give flexible spring suspension of the arch from a more or less vertical position thereabove.

5. A foot-supporter comprising a shoe having a socket in the heel thereof, a flexible spring rod extending vertically of one side of the shoe with one end engaged in said socket, and a flexible strap fixed at one end to the outer edge of the shank of the insole for positioning crosswise of the shank and under the arch of the foot with its free end terminating at a point vertically above the shoe on the inner side thereof and below and laterally remote from the upper end of the rod, said strap having means at its free end for connection with the upper end of the rod and said rod being offset relatively to the strap when the latter is in arch-supporting position within the shoe so as to require distortion of its upper end forwardly and downwardly and inwardly for connection with the free end of the strap.

6. A foot-supporter comprising a shoe, a strap adapted to extend under the arch of the foot and fastened at one end within the shoe, and a spring suspension member fixed to the shoe and connected with the other end of the strap to resiliently suspend the same in raised position relative to the insole of the shoe, said strap and said spring member being so combined, constructed and arranged relative to each other and to the shoe that when the strap is engaged by and drawn down in the shoe by the pressure of the foot thereagainst of the spring member will be torsionally deformed and will exert a twisting lift, side and back pull to the arch and ankle.

7. A foot-supporter comprising a shoe having an external socket on the side thereof corresponding to the outer side of the foot, a flexible spring fixed in said socket and extending vertically upward therefrom with its free end above the top of the shoe, and a flexible strap suspended from the upward end of the spring and pivotally attached at its lower end to the outer edge of the shank of the insole of the shoe to be drawn down and forwardly in position under the arch of the foot by the pressure of the latter thereagainst with a resultant downward and torsional flexion of the said spring.

8. A foot-supporter comprising a shoe having a socket on one side thereof, a spring rod supported in said socket and extending vertically upward therefrom and above the top of the shoe with its upper end disposed over the outer edge of the insole and rearwardly of the shank of the insole, and a strap suspended from the upper end of the spring rod and attached at its lower end to the outer edge of the shank of the shoe to provide a foot receiving sling adapted against the resistance of the rod to be drawn down into the shoe and to be held in position under the arch by the pressure of the foot.

9. A foot-supporter comprising a shoe, a spring rod having one end attached to the shoe and its free end substantially at a vertical elevation above the top of the shoe, and a flexible strap suspended

from the free end of the rod and attached to the inside of the shoe to provide jointly with the rod a foot receiving sling extending transversely of and above the outer upper of the shoe, said strap serving as an arch-engaging member to be drawn down into the shoe and to be held in position under the arch of the foot by the pressure of the foot thereagainst and said rod being tensioned to hold the strap taut for applying 5 pending pressure to the said arch.

10. The combination with a shoe of a foot-supporter comprising a spring suspension member and a flexible arch-engaging member connected together at one end and fixed to the shoe at their

other ends so as to extend vertically upward of the outer quarter of the shoe with the arch-engaging member adjacent the inner side of the said quarter and held taut by the tension of the spring member, said spring member being on the outside of the said quarter whereby when the arch-engaging member is positioned transversely under the arch of the foot and drawn down into the shoe by the pressure of the arch thereagainst the spring member is flexed inwardly to dispose its upper or suspension end in a position more or less vertically above the opposite or inner side of the shoe. 5 10
